UNITED STATES PATENT OFFICE.

WILLIAM A. GRAU AND MERLE G. MILLER, OF CHICAGO, ILLINOIS.

INDOOR GAME.

Application filed October 25, 1922. Serial No. 596,717.

To all whom it may concern:

Be it known that we, WILLIAM A. GRAU and MERLE G. MILLER, citizens of the United States, residing at Chicago, in the county of Cook and State of Illinois, have invented certain new and useful Improvements in Indoor Games, of which the following is a specification.

This invention relates to indoor games and its object is to provide simple means whereby a game patterned after golf may be played upon a table and furnish much pleasure and amusement to the players.

Our invention contemplates the provision of a board having a miniature golf course laid out thereon, and a movable stand adapted to be moved from place to place and having a miniature golf club flexibly supported thereon so that it can be swung by pressure of the finger to tension a spring and then released to permit the spring to swing the club freely against a ball to drive the ball over the course on the board. After each stroke the stand is moved to position the head of the club for the next stroke and provision is made for changing the clubs as desired.

In the accompanying drawings we have illustrated a selected embodiment of the invention and referring thereto.

Fig. 1 is a perspective view of the stand and club;

Fig. 2 is a detail sectional view;

Fig. 3 is a transverse sectional view on the line 3—3 of Fig. 2;

Fig. 4 is an elevation showing the normal position of the club in full lines and the elevated position of the club in broken lines;

Fig. 5 is a plan view of a board having a miniature golf club thereon.

Fig. 6 is a detail view of a modification.

Referring to the drawings, the stand comprises a base 6 and a standard 7 rigidly mounted on the base and having its upper part bent at a right angle to form a supporting arm 8. A sleeve 9 is mounted on the arm 8 and a sleeve 10 is riveted, soldered or otherwise rigidly mounted on one side of the sleeve 9 and transversely thereof so that the two sleeves are located substantially at right angles to each other. The staff 11 of the golf club is held in proper position in the sleeve 10 by the spring tongue 12 on the sleeve which engages the flat face 13 on the staff. A coil spring 14 on the arm 8 has one end 15 made fast to the standard 7 and its other end 16 is secured to the sleeve 10. The board 17 is shown made in one piece but it may be made in two or more pieces suitably hinged together for convenience in storing and transporting as will be readily understood. This board is surrounded with a border rail 18 and it has a surface coating of sand to resemble a natural earth surface. The sand may be applied in any suitable way and sand paper may be used by stretching it upon and securing it to the board. The course is laid out in any suitable arrangement of tees, fairways, bunkers, traps, hazards and putting greens. The drawings illustrate a nine hole course with the numbers on the putting greens 19 to indicate the general layout. These putting greens may be conveniently made by pasting a sheet of felt of a desired size and shape upon the board and we have found felt such as is used upon billiard and other game tables admirably suited for the purpose. The bunkers 20 may be made with molders' clay, paper pulp or other such materials and suitably affixed to the board. We do not limit ourselves to any particular arrangement of the golf course because it can obviously be made to correspond with local courses or according to some original plan; the bunkers, traps and hazards may be differently arranged and increased or decreased as it may be desired to make the course more difficult or easy.

In practicing our invention the ball will be located on the first tee, the stand will be positioned adjacent the ball so that the head 11' of the club is in the proper position behind the ball 21. Then the player presses upon the handle end of the staff, swinging the club on the arm as a fulcrum to a position substantially as shown in the broken lines in Fig. 4, and during the movement of the sleeves in swinging the club to this broken line position the coil spring is tensioned so that when the finger is released from the staff the club is swung out to cause its head to strike the ball for a drive or an approach or a putt or for any other stroke common to the golf game. The construction is such that a set of clubs may be provided and they can be readily changed as required for different strokes; or a single club with a universal head may be used which will answer the purposes of affording pleasure and amusement. The base of

the standard may be made heavy and substantial enough to hold the club steady while it is being swung but we prefer to make it of sufficient breadth as shown to permit 5 fingers of the left hand to be placed thereon on opposite sides of the standard to steady it during the manipulation of the club. The stand is moved around from place to place as required in following the ball, and the 10 well known rules of the golf game may be observed or any other rules may be adopted as desired. Of course the pleasure of the game is enhanced by the skill developed in the force applied to the club in striking 15 the ball on a miniature course.

We are aware that the layout of the golf course may be changed in many ways and that the construction of the stand and its associated parts may be altered as required 20 to suit various conditions, without departing from the invention and we reserve the right to make all such changes as fairly fall within the scope of the following claims. For example, we have shown a slightly modified construction in Fig. 6 wherein the arm 25 21' is bored to receive the shank 22 of the head 23 in which the staff 24 of the club is held. The shank has its end 25 riveted or otherwise provided with means to prevent 30 its disengagement from the arm. A spring 26 is secured at one end to the arm 21 and at its other end to the head 23 and, like

the spring 14, is adapted to be tensioned when the club is swung to the broken line position of Fig. 4 and to swing the club 35 downward to strike the ball, as hereinbefore described.

We claim:

1. The combination of a base, a standard on the base, a substantially horizontal arm 40 on the standard, a horizontal sleeve on the arm, a vertical sleeve on the horizontal sleeve, a miniature golf club detachably engaged with the vertical sleeve and a spring attached at one end to the standard and having its other end engaged with the golf club and adapted to be tensioned when the club is swung to substantially horizontal position to cause the club to swing and strike a ball positioned adjacent the base. 45

2. The combination of a base, a standard on the base, an arm on the standard, an open ended sleeve supported to swing on the arm at right angles thereto, a miniature golf club extending through said sleeve and removable and adjustable endwise therethrough, a spring tongue on the sleeve engaging the club to hold it in place in the sleeve, and means for swinging the club from a substantially horizontal position to 55 strike a ball positioned adjacent the base. 60
